UNITED STATES PATENT OFFICE.

ARTHUR W. WALKER, OF MALDEN, MASSACHUSETTS.

COOKING STOVE AND RANGE.

1,163,796.

Specification of Letters Patent. Patented Dec. 14, 1915.

Application filed October 27, 1910. Serial No. 589,845.

To all whom it may concern:

Be it known that I, ARTHUR W. WALKER, a citizen of the United States, residing at Malden, in the county of Middlesex and State of Massachusetts, have invented certain new and useful Improvements in Cooking Stoves and Ranges, of which the following is a specification.

This invention relates mainly to convertible cooking stoves and ranges, that is to say, to stoves and ranges of that type in which provision is made for supplying heat to the oven either from its exterior, as by means of solid fuel burned in the fire box, or internally by means of gas or liquid fuel burned within the oven or at or adjacent to its bottom, and is particularly intended to provide a simple and practical stove of the character above referred to which may be readily arranged for use with either form of fuel without the addition to the stove of various attachments required heretofore. Certain features of the invention, however, are of wider applicability and may be embodied in a non-convertible cooking stove or range.

In the accompanying drawings:—Figure 1 is a vertical longitudinal section through the body portion of a convertible stove embodying my improvements, as preferably constructed; Fig. 2 is a front elevation on a larger scale, showing the oven door and adjacent parts with the door in closed position; Fig. 3 is a section on the line 3—3 in Fig. 2; Fig. 4 is a vertical longitudinal section through the oven showing a slightly modified arrangement of the parts contained therein; Fig. 5 is a view corresponding to the left hand end of Fig. 4 but showing the parts in a different position; Fig. 6 is a section on the line 6—6 in Fig. 4, showing the oven from front to back, the middle portion of the oven being broken away; Fig. 7 is an elevation of a movable partition hereinafter described; Figs. 8, 9 and 10 are sectional views similar to Figs. 4, 5 and 6, and further illustrating the construction shown in Figs. 1 and 2; Figs. 11 and 12 are detail views of parts hereinafter described. Fig. 13 is a detail view in horizontal section on the line 13—13 in Fig. 2, with certain parts omitted; and Fig. 14 is a view similar to Fig. 4, illustrating a modification.

The stove illustrated in the drawings comprises a body 2 having the usual fire

box 3, an oven 4, and flues 5 located between the oven 4 and the surrounding body 2, the door of the oven being shown at 6. Within the oven are located two partitions 7, 7, 60 which are so arranged that they may be moved at will into the position shown in Fig. 4, in which they occupy an upright position at suitable distances from the sides of the oven to provide flues between the latter and the partitions when the oven is to be heated by gas, or moved out of the way when it is desired to heat the oven by means of fuel burned in the fire box 3. This movement of the partitions 7 may be provided 70 for in various ways, but preferably, as in the particular construction illustrated, each partition is provided at suitable points with pivoted links 8 so proportioned and arranged as to permit the partitions to be 75 moved upward and backward against the respective sides of the oven as shown in Fig. 5, where they may be locked by suitable means such as is hereinafter described.

In addition to the partitions 7 the oven 4 80 is provided with one or more bottom burners suitable for the fuel intended to be used, each burner being so arranged that it may be moved into suitable position for use in burning the fuel employed, or moved out 85 of the way when the oven is to be heated by means of coal or other fuel burned in the fire box. Various forms of burner may be utilized and the desired movement of the same may be provided for in any suitable 90 manner, but according to the construction illustrated in the drawings two similar gas burners are employed, each burner consisting of a pipe 9 extending from the front to the back of the oven and having perforations 10 or other openings for the escape of the mixed gas and air from the pipe when the burner is in use. Each of these pipes 9 is pivotally mounted within the oven in such manner that the perforated portion of the 100 pipe may be caused to rest upon the floor of the oven or swung upward toward one side of the same, as shown in Figs. 4 and 5, respectively, to which end each burner (shown in detail in Fig. 12) is provided at 105 one end with an offset pivot 11 adapted to enter a suitable recess in the back wall of the oven, while its other end portion is bent outward in line with the pivot 11, as at 12, and located within a perforation in the 110 front wall of the oven adjacent to one of the lower front corners thereof, where its outer

end is located on the exterior of the oven and receives the turns on the free end of a supply pipe 13 carried by the framework of the stove and provided with the usual stop 5 cock 14 for regulating the supply of gas. Provision is also made for supplying air to the burner in connection with the gas which enters it, as by means of openings 15 in the outer end of the burner, adjacent to 10 the discharge end of the supply pipe 13, which openings may be regulated in size by an adjustable damper 16 in the usual manner.

In the construction shown in Figs. 4, 5, 6 15 and 7, the partitions and burners are each movable independently of the others, but in order to simplify the operation of arranging the parts for use in connection with either fuel, I prefer to connect the partitions 20 and burners in such manner that the operation of one will operate the other. Such an arrangement is illustrated in Figs. 1, 2, 3, 8 and 9, in which the lower end of each partition 7' is pivoted to the adjacent burner 25 in such manner that the burner takes the place of the lowermost links 8 shown in Fig. 4. With this arrangement, when either burner is swung upward toward the corresponding side of the oven the corresponding partition is lifted with it, and in order to keep the oven as clear as possible from obstructing parts the side walls thereof are preferably offset outwardly at their lower portions, as shown at 17, to receive the adjacent burners, and the lower portions of the partitions 7' are similarly offset to fit between the burners and the off-set portions of the oven walls, so that when the burners and partitions are moved upward they will 30 lie flat against the side walls of the oven and will not occupy any substantial portion of its interior, as shown in Fig. 9. The burners may be locked in this position by means of pivoted hooks 18 each arranged 35 to engage a pin 19 carried by the corresponding burner, and the partitions will evidently be held in their uppermost position by the burners whether the partitions and burners are connected to each other or 40 not, in case the offset arrangement above described is employed.

As thus constructed, the oven is arranged for use with coal as a fuel by moving the burners and partitions upward and backward 45 against the sides of the oven and securing them in such position as already described, in which position of said parts the interior of the oven is substantially unobstructed by the contained parts and has its 50 full capacity to receive its intended contents, the partitions 7 and 7' being preferably provided with a suitable number of ledges 20 adapted to support one or more shelves 21, on which various articles may 55 be placed. When it is desired to heat the

oven by means of gas the burners and partitions are moved into the position shown in Figs. 1 and 4 and a false bottom 22 is inserted into the oven above the burners, thus providing an interior oven of slightly reduced capacity, which may be heated by admitting gas to the pipes 9 and lighting the gas beneath the false bottom 22. The spaces left between the partitions 7 or 7' and the side walls of the oven, in connection with 70 openings 23 formed in the lower edges of the partitions below the level of the false bottom 22, provide flues through which the hot gases resulting from the combustion pass upward between the partitions and the side 75 walls of the oven, and these products of combustion are preferably admitted to the interior oven through openings 24 formed in the partitions between the ledges 20, so that the hot gases thus come in direct contact with the articles to be cooked, as is customary in gas-heated ovens. In order to limit the movement of these hot gases to the path just indicated, the oven door is provided, wherever necessary, with inwardly-projecting ledges or flanges 25 arranged in alinement with the lowered partitions 7 or 7' and adapted to come into close proximity to the front edges of the same when the oven door is closed, (see Fig. 13) 80 so that the gases are prevented from passing around the front edges of the partitions between the same and the door.

Provision is made for the escape of the products of combustion from the oven by providing the latter with one or more suitable outlet openings, such as 26, and in the drawings I have shown an arrangement for automatically opening these outlet openings when the parts are arranged for the use 100 of gas as a fuel and for automatically closing said openings at other times. This is accomplished by means of dampers 27, one for each opening, each damper being mounted on one of the walls of the oven and connected at one end with one of the movable parts, such as the adjacent partition 7 or 7', in such manner that when said movable parts are held against the side walls of the oven the dampers 27 are located directly in front of and close to the openings 26, while when said movable parts are in position for the use of gas the dampers are moved away from the openings, as shown in Fig. 1, for example. In the particular constructions illustrated, each damper 27 is pivotally mounted on the rear wall of the oven and provided at one end with a slot 28 which receives a pin 29 fixed to the corresponding partition 7 or 7'. Provision may 105 also be made, if desired, for admitting air to the interior of the gas oven, as by providing the oven door 6 with one or more dampers 30, each hinged thereto in such manner as to automatically close an opening 110

31 formed in the door when the false bottom 22 is removed and the partitions and burners are folded up against the side walls of the oven. When said parts are in position for use, however, one of them, such as the pipe 9, is located in position to be engaged by the end of an arm 32 carried by the corresponding damper 30 when the oven door is closed, thus causing said damper to swing outward and open the aperture beneath it, as shown in Fig. 3.

The ledges 20 on the partitions 7 and 7' serve to support shelves within the oven when gas is burned, just as they serve the same purpose when said partitions are folded against the side walls of the oven, except that in the latter case the shelves must be wider than in the former case in order to rest upon the ledges. Therefore, in order to avoid the employment of two sets of shelves, I form each shelf 21 of such a size that in one dimension it is wide enough to rest upon the ledges 20 when the partitions are moved upward and backward, while its other dimension is such that it will rest upon said ledges when the partitions are in their innermost position, so that each shelf may be used in connection with either arrangement of the parts contained within the oven.

30 Instead of employing two internal partitions for the purpose above described, one such partition may be utilized in connection with any suitable number and arrangement of burners, in which case the ledges on said partition will coöperate with the opposite ledges such as are commonly provided on the side walls of the oven in non-convertible stoves. Such a construction is illustrated in Fig. 14, which shows an oven containing at its left hand side a movable partition and burner like those already described, while the right hand side of the oven is merely provided with ledges 20' so arranged as to coöperate with the ledges 20 on the movable partition in either position of the latter for the purpose of holding shelves. That partition which is nearest the fire box 3 is also capable of serving a useful purpose independently of any gas burner, in that it may be used when moved inward or away from the side wall of the oven as a baking shield for securing uniformity in the heating of the oven by means of the fuel in the fire box, this feature of my invention being applicable to non-convertible cooking stoves and ranges. The movable partitions or either of them may also be used in connection with a fixed broiling burner, such a burner being indicated at 33 in Fig. 4, or with various other forms and arrangements of burners, and the features and details of the construction illustrated and described may be widely modified in other particulars without departing from the substance of my invention, as will be evident.

I claim as my invention:—

1. In a cooking stove, the combination with the fire box and oven of an upright partition contained within the oven and pivotal connections between the same and the oven to permit said partition to be located bodily at a distance from the adjacent side wall of the oven or held against the same. 70

2. In a cooking stove, the combination with the fire box and oven of an upright partition contained within the oven, and pivotal links connecting said oven and partition, whereby the latter is adapted to be located in substantially parallel relation to the adjacent side wall of the oven at a distance therefrom, or held against the same. 75

3. In a cooking stove, the combination with the fire box and oven of an upright partition contained within the oven and pivotal connections between the same and the oven to permit said partition to be located bodily at a distance from the adjacent side wall of the oven or held against the same, a burner located within said oven, and a false bottom adapted to be located above 90 said burner. 85

4. In a cooking stove, the combination with the fire box and oven of a pair of side partitions connected to the oven within the latter and each adapted to be located bodily at a distance from the adjacent side walls of the oven or held against the same, a false bottom adapted to be moved into and out of operative position within said oven, and a burner adapted to be located beneath said 100 false bottom. 95

5. In a cooking stove, the combination with the fire box and oven of a burner contained within said oven and mounted on pivots located in one of the lower corners 105 thereof, whereby said burner is adapted to be moved into operative position over the floor of the oven or swung upward against the adjacent side wall of the same, and a false bottom adapted to be located above 110 said burner when the latter is in operative position. 115

6. In a cooking stove, the combination with the fire box and oven of a burner contained within said oven and mounted on pivots located in one of the lower side corners of the latter, whereby said burner is adapted to be moved into operative position over the floor of the oven or swung upward against the adjacent side wall of the same, pipe connections extending inward from the front of the oven for admitting fuel to said burner through its front pivot, and a false bottom adapted to be located above said burner when the latter is in its operative 120 position. 125

7. In a cooking stove, the combination with the fire box and oven of a burner contained within said oven and mounted on pivots located in one of the lower corners 130

thereof, whereby said burner is adapted to be moved into operative position over the floor of the oven or swung upward against the adjacent side wall of the same, said side wall being provided with a recess to receive the burner when swung upward.

8. In a cooking stove, the combination with the fire box and oven of a burner contained within the oven and mounted on pivots located in one of the lower corners thereof, whereby said burner is adapted to be moved into operative position over the floor of the oven or swung against the adjacent side wall of the same, said side wall being provided with a recess to receive the burner when swung upward, and a false bottom adapted to be located above said burner when the latter is in its operative position.

9. In a cooking stove, the combination with the fire box and oven of a burner contained within said oven and mounted on pivots located in one of the lower corners thereof, whereby said burner is adapted to be moved into operative position over the floor of the oven or swung upward against the adjacent side wall of the same, and independently movable side and bottom walls adapted to form within said oven a supplementary oven of reduced dimensions, with the bottom of the same located above said burner when in operative position.

10. In a cooking stove, the combination with the firebox and oven of a partition connected to the oven within the latter and adapted to be located at a distance from a side wall of the oven or held against the same, a burner contained within the oven and movable therein into and out of operative position on the floor of the same, and a false bottom adapted to be located above said burner.

11. In a cooking stove, the combination with the fire box and oven of side partitions connected to the oven within the latter and adapted to be located at a distance from the side walls of the oven or held against the same, pivotally-mounted burners contained within the oven and arranged to swing into and out of operative position on the floor of the latter, and a false bottom adapted to be located above said burners.

12. In a cooking stove, the combination with the fire box and oven, said oven having offset side walls, of side partitions connected to the oven within the latter and adapted to be located at a distance from its side walls or held against the same, said partitions being offset to conform to said side walls, and pivotally-mounted burners contained within the oven and arranged to be located in operative position at the bottom of the latter or swung upward against the offset portions of the respective partitions.

13. In a cooking stove, the combination with the fire box and oven of a partition connected to the oven within the latter and adapted to be located at a distance from the side wall of the oven or held against the same, a burner contained within the oven and arranged to be moved into and out of operative position therein, and connections between said burner and partition for operating the same simultaneously.

14. In a cooking stove, the combination with the fire box and oven of a pair of partitions movably connected to the oven, within the latter, a pair of burners movably mounted within the oven, and connections between each burner and the corresponding partition for operating the same simultaneously.

15. In a cooking stove, the combination with the fire box and oven of a pair of burners pivotally-mounted within the oven and arranged to move between the bottom of the latter and the adjacent side walls of the oven, and a pair of partitions contained within the oven, each partition being movably connected at its upper end to a wall of the oven and at its lower end to the corresponding burner.

16. In a cooking stove, the combination with the fire box and oven of perforated partitions movably connected to the oven, within the latter, and adapted to be located at a distance from the side walls of the oven or held against the same, a false bottom adapted to be located within the oven, means for heating the oven internally beneath said false bottom, and flanges carried by the oven door and arranged to come into close proximity to the front edges of the partitions when the door is closed and said partitions are in their inward position.

17. In a cooking stove, the combination with the fire box and oven of movable walls adapted to form within said oven a supplementary oven of reduced dimensions, with the front edges of said walls located adjacent to the front of the oven, means within the main oven and external to the supplementary oven for heating the latter, and an outwardly-convex door adapted to close the main oven and provided on its concave side at a distance from its edges with inwardly-projecting ledges arranged to come into close proximity to the front edges of the walls of the supplementary oven when said door is closed.

18. In a cooking stove, the combination with the fire box and oven of a movable partition and a movable burner contained therein, the walls of said oven being provided with an opening, and a damper operated by the movement of one of said contained parts for controlling said opening.

19. In a cooking stove, the combination with the fire box and oven of a movable

partition and a movable burner contained therein, said oven being provided with an opening for admitting air thereto, a damper controlling said opening, and means operated by the closing of the door of the oven for opening said damper whenever the contained parts are arranged in operative position.

20. In a cooking stove, the combination 10 with the fire box and oven of side partitions connected to the oven within the latter and arranged to be moved toward and away from the side walls of the same, said parti-

tions being provided with opposed ledges, means for heating the oven internally, and 15 a shelf of such length and width as to rest on said ledges in either position of the partitions.

In testimony whereof, I have hereunto subscribed my name this 24th day of Oc- 20 tober, 1910.

ARTHUR W. WALKER.
